Primary Examiner — Cynthia Underwood(74) *Attorney, Agent, or Firm* — QuickPatents; Kevin Prince(57) **CLAIM**

I claim the ornamental design for a saddle rope holder, as shown and described.

DESCRIPTION

FIG. 1 is a perspective view of a saddle rope holder, showing my new design shown in a position of use;

FIG. 2 is a perspective view shown in a flat configuration;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a saddle and rope in FIG. 1 depict environmental matter and form no part of the claimed design. The boundary lines next to the star represent the boundary of the claim.
